PAGE 4

FIG. 6

FIG. 7

FIG. 1 is a perspective view of an aerospace craft showing my new design;

FIG. 2 is a top plan view thereof;

FIG. 3 is a bottom plan view thereof;

FIG. 4 is a side elevational view thereof, the landing gear being in operating position;

FIG. 5 is an elevational view of the opposite side thereof;

FIG. 6 is a front elevational view thereof; and

FIG. 7 is a rear elevational view thereof, the landing gear being in operating position.

I claim:

The ornamental design for an aerospace craft as shown and described.
